POLISHING MACHINE

Archie L. Burrows, Detroit, and Axel Edwin Henricson, Walnut Lake, Mich., assignors to Motor Products Corporation, Detroit, Mich., a corporation of New York

Application February 14, 1938, Serial No. 190,486

8 Claims. (Cl. 51—95)

This invention relates generally to polishing machines and has as one of its principal objects to provide a relatively simple inexpensive machine embodying means for effectively polishing surfaces without scratching or otherwise marring the surface.

The invention concerns itself more particularly with a polishing machine having a revoluble buffing or polishing wheel and having provision for relatively moving the surface to be polished and the buffing wheel axially of the peripheral or polishing surface of the wheel during the polishing operation. With this arrangement, the life of the buffing wheel is appreciably increased since substantially the entire width of the wheel is used in performing the polishing operation and the resulting rubbing motion is such as to effect a smooth surface free from polishing marks or scratches.

An advantageous feature of the present invention resides in the provision of a polishing machine having means for advancing the surface to be polished relative to the wheel and having means for simultaneously moving the advancing means in a direction transverse to the path of advancement of the surface to such an extent that the entire peripheral surface of the buffing wheel is used to effect the polishing operation. As a result, any wear of the buffing wheel will be distributed uniformly along the polishing surface thereof and the desired degree of polishing is effected without marking the surface.

Another object of this invention consists in the provision of a polishing machine rendering it possible to effectively polish strips of stock of irregular cross sectional and longitudinal contour. This feature is particularly advantageous in the manufacture of vehicle bodies in that it affords a relatively simple means for polishing the molding strips employed in various different parts of the body.

In addition to the foregoing, the present invention contemplates a polishing machine wherein the buffing wheel and mechanism for rotating the latter may be entirely independent of the remaining parts of the apparatus with the result that the buffing wheel may be adapted to the drive shaft of a conventional lathe or other standard type of machine.

The foregoing, as well as other objects, will be made more apparent as this description proceeds, especially when considered in connection with the accompanying drawings, wherein:

Figure 1 is an elevational view, partly in sec-

tion, of a polishing machine constructed in accordance with this invention;

Figure 2 is a side elevational view, partly in section, of the construction shown in Figure 1;

Figure 3 is a top plan view of the apparatus shown in Figure 2;

Figure 4 is a sectional view taken substantially on the plane indicated by the line 4—4 of Figure 3;

Figure 5 is a cross sectional view taken substantially on the plane indicated by the line 5—5 of Figure 3;

Figure 6 is a fragmentary plan view of a slightly modified form of construction;

Figure 7 is a sectional view taken substantially on the plane indicated by the line 7—7 of Figure 6; and

Figure 8 is a sectional view taken substantially on the plane indicated by the line 8—8 of Figure 1.

For the purpose of illustrating the present invention, we have selected two molding strips of different configuration, although it will be readily apparent as this description proceeds that the principles involved are by no means limited to polishing strips of the particular configuration illustrated. In the embodiment of the invention illustrated in Figures 1 to 5, inclusive, the strip A is shown as having a longitudinal curvature of the type illustrated in Figure 2 and as having a cross sectional contour of the character noted in Figures 1 and 4.

In general, the strip A is removably secured to the top surface of a support 10 having a track 11 at the underside thereof adapted to extend between a pair of rolls 12 and 13 in a manner to be frictionally engaged by the peripheral surfaces of the rolls. As will be presently set forth, the rolls are operatively connected to a prime mover 14 through the medium of suitable speed reducing mechanism 15 in a manner to be rotated in opposite directions, with the result that the track 11 is advanced by the rolls throughout a path of travel dependent upon the longitudinal contour of the track. The longitudinal contour of the track conforms substantially to the longitudinal contour of the molding strip A to be polished so that this molding strip is advanced throughout a corresponding path of travel. A buffing wheel 16 of suitable construction is revolvably supported in a position above one point in the path of travel of the molding strip A and is preferably located to engage the surface of the molding A directly opposite the advancing rolls 12 and 13. It will, of course, be understood

that the molding A is attached to the top surface of the support 10 directly above the track 11 fastened to the undersurface of the support so that as the molding is advanced by the track, the top surface of the molding is progressively engaged by the periphery of the buffing wheel 16.

In the present instance, the advancing rolls and, accordingly, the support 10 with the molding A thereon are moved in opposite directions 10 transverse to the path of travel of the molding during advancement of the latter relative to the buffing wheel. The degree of motion of the molding A in the above named directions is determined so that the entire width of the buffing 15 wheel is used to effect the polishing operation, and this is advantageous in that any wear of the buffing wheel is uniformly distributed throughout the axial extent of the periphery of the wheel with the result that the life of the latter is appreciably increased. In addition, the aforesaid transverse movement of the molding relative to the buffing wheel cooperates with the rotary movement of the latter and the advancing movement of the molding to provide a combination 20 of motions which render it possible to effectively polish the molding A without scratching, or otherwise marring the surface of the latter. Attention may also be called to the fact at this time that movement of the molding A 25 axially of the buffing wheel is more advantageous than moving the buffing wheel axially relative to the molding for the reason that the driving means for the buffing wheel is not only appreciably simplified but, in addition, the buffing wheel may be mounted on the drive shaft of 30 a conventional lathe or other standard machine equipped with a revolute shaft. In other words, the buffing wheel may be a unit separate from the unit for imparting the aforesaid motions to the molding and no special provision need be 35 made for driving the polishing wheel.

Referring now more in detail to the particular construction of the polishing machine forming the subject matter of this invention, it will be noted from Figures 1 and 2 that the machine is provided with a base 20 and a pedestal 21 supported on the base for sliding movement in the direction of the axis of rotation of the buffing wheel 16 in order to accurately position 40 the advancing rolls relative to the buffing wheel. The base 20 is shown in the above figures as having a dove-tailed projection 22 extending in the direction of sliding movement of the pedestal and adapted to slidably engage in a correspondingly shaped way 23 formed in the undersurface 45 of the pedestal base 24. Accurate adjustment of the pedestal 21 relative to the base 20 is effected by means of a screw 25 rotatably supported in the base 20 and having a portion at 50 the inner end threadedly engaging a nut 26 which, in turn, is fixed to the pedestal base 24 by means of the set screws 27. The outer end of the screw is polygonal in cross section and is located to be accessible for manipulation by the operator. From the above, it will be noted that 55 the advancing rolls 12 and 13 may be accurately positioned with respect to the buffing wheels 16 by accurately adjusting the screw 25 on the base 20 relative to the nut 26 on the pedestal.

70 Formed integral with the pedestal base 24 is an upwardly extending tubular portion 28 adapted to telescopically receive a screw 29 secured against rotation relative to the tubular portion 28 by means of a screw 30 threaded in the side 75 wall of the tubular portion with the inner end

slidably engaging in an axially extending keyway 31 formed in one side of the screw 29. A nut 32 is rotatably supported on the upper edge of the tubular portion 28 of the pedestal and has a threaded engagement with the screw 29 so that 5 rotation of the nut relative to the screw causes the latter to move, either upwardly or downwardly, depending upon the direction of rotation of the nut. In this manner, the elevation of the molding strip A may be varied with respect to 10 the periphery of the polishing wheel 16 and the proper polishing pressure may be applied to the molding strip. Accidental rotation of the nut 32 relative to the screw 29 is prevented by effectively clamping the screw in the tubular portion 28. In detail, the tubular portion 28 is axially slotted at one side in the manner designated by the reference character 33 and the portions on opposite sides of the slot adjacent the upper end of the latter are formed with laterally outwardly extending ears 34 and 35. Upon reference to Figure 2, it will be noted that the ears are formed with aligned openings therethrough and that the ear 35 is internally threaded for threaded engagement with a shaft 25 36 which extends freely through the ear 34. A suitable handle 37 is secured to the extremity of the shaft in the manner shown so that movement of the handle in one direction places the tubular portion 28 under sufficient stress to clamp the 30 screw against movement relative to the tubular portion 28 and movement of the handle in the opposite direction releases this stress to permit the desired adjustment of the screw 29 by the nut 32. 35

The upper end of the screw 29 is shown in Figure 2 as being substantially U-shaped in end elevation and as having a dove-tailed projection 38 extending upwardly from the base 39 and adapted to be slidably received in a correspondingly shaped way 40 formed in the undersurface of a plate 41 which is located between the legs 42 of the U-shaped portion. The gib 38 and cooperating way 40 extend in the direction of the axis of rotation of the buffing wheel 16, and the legs 42 of the U-shaped portion on the screw 29 are respectively located on opposite sides of the path of travel of the plate 41 relative to the screw 29. 45

As will be more fully hereinafter set forth, the 50 advancing rolls 12 and 13 are carried by the plate 41 and, as a consequence, are movable with the plate in the direction of the axis of the buffing wheel 16. In detail, the opposite ends of the plate 41 are provided with upwardly extending supporting plates 43 having a table or platform 44 resting upon the top edge portions of the plates 43 and secured to the latter edges by means of the screws 45. As shown in Figure 4 of the drawings, the two advancing rolls 12 and 60 13 extend upwardly through openings formed in the platform 44 in such a manner that movement of the plate 41 relative to the upper end of the screw 29 effects a corresponding movement of the advancing rolls relative to the buffing wheel. 65

The prime mover 14 and speed reducer 15 are supported on one of the vertical plates 43 within the space defined by these plates and the platform 44. In other words, the prime mover 14 and speed reducer 15 are movable with the plate 41 and platform 44 in the direction of the axis of rotation of the buffing wheel 16. Upon reference to Figures 1 and 2 of the drawings, it will be noted that the speed reducer is provided with a 70 75

power take-off shaft 45' having its axis extending vertically and operatively connected to the drive shaft of the prime mover 14 through the medium of reduction gearing (not shown) in a 5 manner to be driven by the prime mover 14 at a reduced speed. The upper end 46 of the power take-off shaft 45' extends beyond the speed reducing unit 15 through an opening 47 in the platform 44 and is adapted to telescopically receive the hub 48 on the advancing roll 12. As shown in Figure 4, the hub 48 is rotatably supported on the platform 44 by means of a flange 49 extending radially outwardly from the hub beneath the roll 12 and frictionally engaging 10 the top surface of the platform 44 surrounding the opening 47. The flange 49 is maintained into frictional engagement with the platform 44 by means of a screw 50 threaded into the upper extremity of the power take-off shaft 45' and having 15 an enlarged head 51 at the upper end thereof seated in a counterbored recess 52 formed in the upper end of the roll 12. Thus, it will be seen that the head 51 cooperates with the flange 49 in securing the roll 12 against axial displacement 20 relative to the power take-off shaft 45'.

The roll 12 is driven from the power take-off shaft 45' by means of a gear 53 keyed to the shaft 45' and having an upwardly extending hub 54 provided with an axially upwardly extending key 30 55 adapted to engage in a slot or keyway 56 formed in the adjacent end of the hub 48 on the roll 12. With this construction, the roll 12 may be assembled in driving engagement with the shaft 45' by merely telescoping the hub 48 of the 35 roll 12 on the upper extremity 46 of the shaft 45' from the top side of the platform 44. It will, of course, be understood that during the interval the roll is sleeved on the upper end 46 of the shaft 45', the roll is rotatably adjusted to register the 40 keyway 56 with the key 55 so that when the roll is in the position thereof shown in Figure 4, the flange 49 on the hub rests upon the top surface of the platform 44 and the key 55 engages in the keyway 56. After the roll 12 has been positioned 45 in this manner, the screw 50 is secured in place to prevent axial displacement of the roll.

The cooperating advancing roll 13 is identical in construction to the roll 12 and is assembled on a vertical shaft 57 in the same manner as the 50 roll 12 is assembled on the upper end 46 of the drive shaft 45'. Attention may be called to the fact, however, that the opening 58 in the platform 44, through which the hub 60 of the advancing roll 13 extends, has a diameter which is greater 55 than the diameter of the hub in order to permit limited shifting movement of the roll 13 toward and away from the cooperating roll 12. In the present instance, the cooperating advancing roll 13 is driven in a direction opposite to the direction of rotation of the roll 12, and this is accomplished by a gear 61 meshing with the gear 53 and rotatably supported on the shaft 57. The gear 61 is also provided with an upwardly extending hub 62 having an axially extending key 63 engageable in a keyway 64 formed in the lower edge of the hub 60 on the forming roll 13. In this manner, the forming roll 13 is driven from the power take-off shaft 45' in a direction opposite to the direction of rotation of the advancing 70 roll 12.

Reference has been made above to the fact that the advancing roll 13 is movable toward and away from the cooperating roll 12. This is accomplished by integrally, or otherwise fixing the lower end of the shaft 57 to a plate 66 secured to

a slide supported on the underside of the platform 44 for shifting movement toward and away from the power take-off shaft 45'. Upon reference to Figure 5 of the drawings, it will be noted that the slide 67 is guided throughout its movement by means of guides 68 fastened to the underside of the platform 44 on opposite sides of the path of travel of the slide 67. The slide is adjusted to provide the desired clearance between the cooperating advancing rolls by means of a screw 70 rotatably supported in a bearing 71 fixed to the platform 44 and having the inner end threaded engaging the outer end portion of the slide 67. The extreme outer end of the screw is polygonal in shape for the purpose of manipulation and axial sliding movement of the screw relative to the bearing 71 is limited by collars 72 fixed to the screw at opposite sides of the bearing. A suitable spring 73 is located between one of the collars and the adjacent side of the bearing 71 to prevent accidental rotation of the screw. 15

It will be apparent from the foregoing that the slide 67, plate 66 carrying the shaft 57, and adjusting screw 70 are all mounted on the platform so as to move as a unit with the platform when 25 the plate 41 is moved in the direction of the axis of the polishing rolls 16 relative to the elevating screw 29. In the present instance, the plate 41, together with the platform 44 and associated parts carried thereby, are reciprocated in the direction of the axis of the polishing rolls 16 during advancement of the strip A along its path of travel relative to the polishing roll. In detail, the lower end 75 of the power take-off shaft 45' is secured to a head 76 in a manner that the 30 head rotates as a unit with the power take-off shaft. As will be presently described, the head is connected to a part, fixed against movement with the plate 41, by a crank arrangement in a manner that the reaction of the crank on the fixed member causes a reciprocation of the plate 41 when the power take-off shaft is rotated. Inasmuch as the advancing rolls are carried by the platform 44 which in turn, is mounted on the plate 41, it follows that the advancing rolls will 35 be correspondingly reciprocated and will move the strip of stock A axially of the periphery of the polishing roll 16 as the strip is advanced relative to the polishing roll. 40

As shown in Figures 1 and 2, the head 76 is 50 formed with a wedge-shaped recess 77 in the bottom surface thereof, and this recess extends at right angles to the axis of rotation of the power take-off shaft 45'. A correspondingly shaped insert 79 is slidably mounted in the recess and has 55 a roller 80 depending from the underside thereof with its axis of rotation offset from the axis of rotation of the power take-off shaft 45' so as to describe an arc around the latter axis upon rotation of the head 76 by the shaft 45'. The 60 roller 80 is, of course, fixed to the wedge 79 and extends beyond the underside of the wedge into a slot 81 formed in a plate 82 which is fixed to the head 39 of the elevating screw 29. The slot 81 is elongated in a direction transverse to the 65 direction of sliding movement of the plate 41 and the longitudinal walls of the slot are frictionally engaged by the roller 80. In the present instance, the opposite ends of the plate 82 fit within recesses 85 formed in the upper ends 70 of the legs 42 of the U-shaped head 39 and are secured to the legs by suitable screws 86.

Inasmuch as the advancing rolls and driving mechanism therefor, including the power take-off shaft 45', are carried by the plate 41 and, 75

in view of the fact that the plate 82 is fixed relative to the plate 41 and is eccentrically connected to the power take-off shaft in the manner described, it follows that rotation of the head 76 by the power take-off shaft 45' effects a reciprocation of the plate 41 and parts carried thereby throughout a distance depending upon the degree of offset of the roller 80 with respect to the axis of rotation of the power take-off shaft. The extent of reciprocation is determined so that substantially the entire polishing surface of the buffing wheel 16 is used to polish the strip of stock during the interval the latter is advanced relative to the buffing wheel. It will, of course, be understood that the length of the slot 81 is sufficient to provide the desired operation without binding, or otherwise stressing the parts.

The degree of offset of the roller 80 with respect to the axis of rotation of the power take-off shaft 45' may be adjusted by sliding the wedge-shaped insert 79 longitudinally of the recess 77 in the head 76. This is accomplished by an adjusting screw 90 rotatably supported in the head 76 and having the inner end portion threadedly engaging the insert. Thus, by turning the adjusting screw 90, the eccentricity of the roller 80 with respect to the axis of rotation of the power take-off shaft 45' may be varied from zero to a predetermined maximum. The wedge 79 is held in any one of its adjusted positions by means of a set screw 92 threaded through one side of the head and adapted to engage the adjacent side of the insert in the manner clearly shown in Figure 2.

As previously stated, a strip of stock A is removably secured to the upper surface of the support 10 directly above the track 11 provided on the undersurface of the support for guiding the stock throughout its movement past the buffing wheel 16. In the present instance, the track 11 is channel-shaped in cross section and is secured to the undersurface of the support 10 with the channel opening toward the advancing roll 12. The distances between the flanges of the channel are such as to receive the periphery of the roll 12 therebetween and permit the latter to engage the inner surface of the base section of the channel. The outer surface of the base of the channel is frictionally engaged by the other advancing roll 13, with the result that the latter cooperates with the roll 12 in advancing the support 10 relative to the polishing wheel. Inasmuch as the molding A is attached to the support, it follows that this molding will be advanced as a unit with the support. In this connection, it will be noted that the support may be provided with suitable projections 100 extending upwardly from the top surface thereof and shaped to telescopically receive the molding strip A. Also, it will be noted that the longitudinal contour of the track 11 conforms to the longitudinal contour of the molding strip A so that the surface of the strip to be polished is brought into registration with the polishing wheel, irrespective of its longitudinal contour.

The embodiment of the invention shown in Figures 6 and 7 is identical to the one previously described, with the exception of the particular configuration of the molding strip being polished. In Figures 6 and 7, the molding strip is designated by the reference character B and has a cross sectional contour, such as to permit dispensing with the support 10 and associated fastening means 11. In other words, the cross sec-

tional contour of the strip B is channel-shaped and may be passed directly between the advancing rolls. It will, of course, be understood that the strip B requires two polishing operations in order to polish the exterior surfaces of both the legs of the channel. In the event that it is desired to polish the base of the channel, it is necessary to introduce the strip to another type of polishing machine.

From the foregoing, it will be apparent that we have provided a relatively simple and inexpensive polishing machine wherein the strip being polished is actually displaced laterally of its path of travel relative to the buffing wheel to such an extent that substantially the entire peripheral surface of the wheel is employed during the polishing operation. As a result, the life of the burnishing wheel is appreciably increased and a better polishing effect is obtained. In addition, it will be noted that the polishing machine renders it possible to effectively polish surfaces of moldings having an irregular longitudinal contour without axially moving the polishing wheel.

What we claim as our invention is:

1. In a polishing machine, a revoluble polishing wheel, means for advancing a strip of stock relative to the wheel with the surface of the stock to be polished adjacent the polishing surface of the wheel, a prime mover for operating the advancing means, a support for both the advancing means and prime mover, and means operated by the prime mover for reciprocating the support in directions to move the stock in opposite directions across the polishing surface of the wheel.

2. In a polishing machine, a revoluble polishing wheel, a pair of rolls cooperating with each other to advance a strip of stock relative to the wheel with the surface of the stock to be polished adjacent the polishing surface of the wheel, a prime mover operatively connected to the rolls for rotating the latter, supporting means for the rolls and prime mover, and means operated by the prime mover for reciprocating the supporting means transversely to the path of advancement and in a plane substantially parallel to the polishing surface of the wheel.

3. In a polishing machine, a revoluble polishing wheel, a pair of rolls cooperating with each other to advance a strip of stock relative to the wheel with the surface of the stock to be polished adjacent the polishing surface of the wheel, mechanism operatively connected to the rolls for rotating the latter, common supporting means for the rolls and mechanism, and means also actuated by said mechanism for reciprocating the support transversely to the path of advancement of the strip and in a plane substantially parallel to the axis of rotation of the polishing wheel.

4. In a polishing machine, a revoluble polishing wheel, a pair of rolls cooperating with each other to advance a strip of stock relative to the wheel with the surface of the stock to be polished adjacent the polishing surface of the wheel, a support for said rolls, a rotatable shaft carried by the support and operatively connected to one of the rolls for rotating the latter, and means driven by the revoluble shaft for reciprocating the supporting means transversely to the path of advancement of the stock and in a plane substantially parallel to the axis of rotation of the polishing wheel.

5. In a polishing machine, a revoluble polishing wheel, a pair of rolls cooperating with each

other to advance a strip of stock relative to the wheel with the surface of the stock to be polished adjacent the polishing surface of the wheel, a support for the cooperating rolls mounted for 5 sliding movement in a direction substantially parallel to the axis of rotation of the polishing wheel, a rotatable shaft carried by the support and operatively connected to one of the rolls for rotating the latter, a member fixed against 10 sliding movement with the support, and a crank arrangement operatively connecting said shaft to the member in a manner to effect the sliding movement aforesaid of the supporting means relative to the polishing wheel during advancement 15 of the strip of stock by said rolls.

6. In a polishing machine, a revolute polishing wheel, a pair of rolls cooperating with each other to advance a strip of stock relative to the wheel with the surface of the stock to be polished 20 adjacent the polishing surface of the wheel, supporting means for the cooperating rolls mounted for sliding movement in a direction transverse to the path of advancement of the strip of stock and in a plane substantially parallel to the axis 25 of rotation of the polishing wheel, a revolute shaft carried by the supporting means and operatively connected to one of the rolls for rotating the latter, a member fixed against sliding movement with the supporting means, a 30 crank arrangement operatively connecting the revolute shaft to said fixed member in a manner to effect sliding movement of the supporting means in the aforesaid direction upon rotation of the shaft, and means for adjusting the throw 35 of the crank to vary the extent of sliding movement of said supporting means.

7. In a polishing machine, a revolute polishing wheel, a pair of rolls cooperating with each other to advance a strip of stock relative to the

wheel with the surface of the stock to be polished adjacent the polishing surface of the wheel, supporting means for the cooperating rolls mounted for sliding movement in a direction transverse to the path of advancement of the strip of stock 5 and in a plane substantially parallel to the axis of rotation of the polishing wheel, a revolute shaft carried by the supporting means and operatively connected to one of the rolls for rotating the latter, a member fixed against sliding 10 movement with the supporting means and having a slot therethrough elongated in a direction transverse to the direction of sliding movement of the supporting means, an element extending into the slot in engagement with the opposed longitudinal walls of the slot and offset from the axis of rotation of the shaft, and means connecting the element to the shaft for rotation thereby. 15

8. In a polishing machine, a revolute polish- 20 ing wheel, a pair of rolls cooperating with each other to advance a strip of stock relative to the wheel with the surface of the stock to be polished adjacent the polishing surface of the wheel, supporting means for the rolls mounted for recip- 25 rocation transverse to the path of advancement of the strip and in a plane substantially parallel to the axis of rotation of the polishing roll, a speed reducing unit carried by the supporting means and having a power take-off shaft opera- 30 tively connected to one of the advancing rolls for rotating the latter, a prime mover also carried by the supporting means for driving the speed reducing unit, and means also driven by the power take-off shaft of the speed reducing unit 35 for reciprocating said supporting means.

ARCHIE L. BURROWS.
